TOILET SEAT AND THE LIKE

Arthur F. Horr, Craigsdale, N. Y.

Application March 16, 1940, Serial No. 324,249

10 Claims. (Cl. 4—233)

This invention relates primarily to toilet seats and has for one of its objects the provision of a construction wherein the seat after use is covered, washed, sterilized by heat and then cooled, so as 5 to be in a clean and sterile condition after each operation. Inasmuch as the cover moves to closed position after each operation and remains closed, the danger of contamination while the apparatus is standing idle is removed.

10 More specifically my invention comprehends a seat having the general characteristics above referred to in which the operation of uncovering the seat for use is initiated manually, as by depressing a pedal or operating a pushbutton, the 15 cover opening thereafter automatically. After use the cover returns to initial position and remains in that position, the seat after closure of the cover being washed, sterilized and cooled.

In the accompanying drawings wherein I have 20 illustrated one embodiment of my invention:

Fig. 1 is an elevational view showing the apparatus in closed position;

Fig. 2 is a view similar to Fig. 1 showing the cover open;

25 Fig. 3 is a plan view partly in section with the seat cover closed;

Fig. 4 is a fragmentary longitudinal section through Fig. 3;

Fig. 5 is a detail view of the cams, switches and 30 valves of the apparatus; and

Fig. 6 is a wiring diagram of the electric circuits employed in the equipment.

Referring to the drawings in detail: 2 designates a toilet bowl to which my invention is applied.

Resiliently mounted on the bowl 2 is a drain pan 4 of metal, for instance. This pan is in the form of an annulus resting upon rubber pads 6 or other resilient mounting, upon the bowl 2, the 40 inner edge of this annulus being bent downwardly so that the pan will drain into the bowl.

8 is the seat which is to be sterilized, etc. This seat is of metal and is hollow or arch-shaped in cross section, as seen in Fig. 4.

45 Intermediate the seat 8 and the pan 4 I provide a water pipe 10 which extends from the rear part of the assembly and is bent around, as illustrated in Fig. 3, to the general contour of the seat. This pipe is provided with perforations in its upper face, as shown at 12, so that when water is supplied to the pipe it will spray the lower side of the seat 8. The function of this spray is to cool the seat after the completion of the sterilizing operation.

50 Overlying the seat 8 is a cover 14 which is

adapted to be raised and lowered, as illustrated in Figs. 2 and 4, for example. Mounted on the lower side of this cover is a water pipe 16, bent to the general contour of the cover and provided in its lower side with perforations so that when 5 water is supplied to the pipe the upper face of the seat 8 will be flushed or washed. This is shown in Fig. 4. The flushing pipe 16 is connected by any suitable form of coupling 18 to fixed pipe 20, so as to permit the pipe 16 to raise and lower with 10 the cover.

Mounted on the pan 4 to the rear of the seat and cover 8 and 14 is a housing 22. Within this housing is an electric driving motor 24 by which the cover 14 is raised and lowered. In axial 15 alignment with the motor 24 is a rotary cam cylinder 26, carrying cams 28, 30 and 32 on its periphery. The cam cylinder is driven by the motor 24 through gear train 34. The shaft 36 of the cam cylinder is mounted in bearings provided 20 in uprights 38, resting, for example, upon the drain pan 4. One of the members 38 is provided with an offset 40 which carries a pinion 42. This pinion meshes at intervals with teeth 44 provided on the inside of the cam cylinder 26. The length 25 of the rack provided by the teeth 44 is such that the pinion 42 makes one revolution only for each revolution of the cam cylinder.

Carried on the face of the pinion 42 is a crank 46 pivotally connected by link 48 to a raising and 30 lowering lever 50, the rear end of which is pivoted at 52; the lever extending forward beneath the cover 14 to which it is pivotally connected at 54.

Extending into the housing 22 is another lever 56 pivoted at its rear end at 58. This lever which 35 may be termed a control lever also extends forward beneath the cover 14 to which it is pivotally connected at 60.

As will be apparent from the drawings, this linkage and lever system is such that upon rotation of the pinion 42 clockwise, as viewed in Fig. 4, for approximately one-half revolution, the cover 14 will be moved rearwardly, its rear end swinging upwardly at the same time until the cover has assumed the broken line position of Fig. 45. In this raising movement the face of the cover is always toward the front of the equipment, which is desirable from the standpoint of appearance and usage. In this movement of the cover it will be appreciated that the lifting is done by 50 the lever 50, the lever 56 acting as a control lever to pivot the rear end of the cover 14 upwardly, until, as above mentioned, the cover assumes a vertical position with the front of the cover facing forwardly.

- position for applying a bath of water to the upper side of the seat, means for thereafter electrically heating the seat to a sterilizing temperature, and means for thereafter applying a coolant 5 to the lower side or face of the seat.
5. An apparatus of the class described, comprising in combination a toilet seat, a cover therefor, automatic controlled power driven means for raising and lowering the cover, means for flushing, 10 ing the seat, for thereafter electrically heating the seat to sterilizing temperature, and means for finally cooling the seat, said flushing, heating and cooling means being cam-controlled, said means being so disposed relatively that the flushing, 15 sterilizing and cooling operations will be performed in the order mentioned and only with the cover in closed position.
6. An apparatus of the class described, comprising in combination a toilet seat, a cover therefor, cam-controlled power driven means for raising 20 and lowering the cover, means for flushing the seat, for thereafter heating the seat to sterilizing temperature, and means for finally cooling the seat, said flushing, heating and cooling means being cam-controlled, said cams being so disposed relatively that the flushing, sterilizing and cooling operations will be performed in the order mentioned and only with the cover in closed position. 25
7. An apparatus of the class described, comprising in combination a toilet seat, a cover therefor, a water pipe attached to the lower side of the cover for supplying a spray of water to the seat when the cover is closed, and means for raising the cover and pipe as a unit. 5
8. An apparatus of the class described, comprising in combination a toilet seat, a cover therefor, a water spray pipe attached to the lower side of the cover, a valve controlling the supplying of water to the said pipe, a lever for raising and lowering the cover, a motor for actuating the lever, and cams driven by said motor for controlling the circuit of the motor and the supplying of water to said pipe, said cams being so relatively disposed that with the cover raised the water supply is shut off to said water pipe. 10
9. An apparatus of the class described, comprising in combination a toilet seat, a cover therefor, a water spray pipe attached to the lower side of the cover, a valve controlling the supplying of water to the said pipe, a lever for raising and lowering the cover, a motor for actuating the lever, and cams driven by said motor for controlling the circuit of the motor and the supplying of water to said pipe, said cams being so relatively disposed that after closure of the cover the said valve will be opened automatically to admit water to the spray pipe. 15
10. An apparatus of the class described, comprising in combination a toilet seat, a cover therefor, power driven means for raising and lowering the cover, electric means for heating the seat, the electric heating means being operative only 20 when the power driven means has lowered the cover to closed position. 25

ARTHUR F. HORN.
